COMBINED WALER BRACKET AND TIE-ROD CLAMP FOR CONCRETE FORMS

Carl M. Jahn, 2640 St. Paul St., Denver, Colo.

Filed Dec. 7, 1959, Ser. No. 58,565

Term of patent 14 years

(Cl. D51—1)

Fig. 1

Fig. 2

Fig. 3

Fig. 4

Fig. 5

FIGURE 1 is a rear perspective view taken from the right side of a combined waler bracket and tie-rod clamp for concrete forms embodying my new design;

FIGURE 2 is a front elevational view thereof, the movable wedge being in the locked position;

FIGURE 3 is a front elevational view thereof, the movable wedge being in the open position;

FIGURE 4 is an elevational view of the left side thereof, the movable wedge being positioned as in FIGURE 2; and

FIGURE 5 is a rear elevational view thereof, the movable wedge being positioned as in FIGURES 2 and 4.

I claim:

The ornamental design for a combined waler bracket and tie-rod clamp for concrete forms, substantially as shown.
